UNITED STATES PATENT OFFICE.

ROBERT MORRELL, OF SUMMIT, NEW JERSEY, ASSIGNOR OF FOURTEEN-TWENTIETHS TO CHARLES S. DAY, AUGUSTUS F. LIBBY, CHARLES F. WOOD, AND GEORGE H. WILLIAMS, OF SAME PLACE, WILLIAM W. McCULLUM, OF MILLBURN, JAMES NEAFIE AND CHARLES BROCK, OF BOONTON, WILLIAM H. LEWIS AND ANDREW REASONER, OF HOBOKEN, FREDERICK NISCHWITZ, OF MILLINGTON, AND CHARLES SIEDLER, OF MORRISTOWN, NEW JERSEY.

RAILWAY-RAIL FASTENING.

SPECIFICATION forming part of Letters Patent No. 483,855, dated October 4, 1892.

Application filed December 29, 1891. Serial No. 416,405. (No model.)

To all whom it may concern:

Be it known that I, ROBERT MORRELL, a citizen of the United States, residing at Summit, in the county of Union and State of New Jersey, have invented certain new and useful Improvements in Railway-Rail Fastenings; and I do declare the following to be a full, clear, and exact description of the invention, such as will enable others skilled in the art to 5 which it appertains to make and use the same, reference being had to the accompanying drawings, and to the letters of reference marked thereon, which form a part of this specification.

15 My invention is in the nature of fastenings whereby railway-rails are secured to metallic ties; and it consists in the improved construction, arrangement, and combination of parts hereinafter fully described, and afterward 20 specifically pointed out in the claims.

25 In the accompanying drawings, Figure 1 is a view in side elevation of a metallic railway-tie with rails in place thereon, secured by my improved fastening. Fig. 2 is a central longitudinal vertical section through the same.

Like letters of reference mark the same parts in both figures of the drawings.

Referring to the drawings by letters, A is the tie, of trough shape, having bottom a and the sides, of trough shape, having bottom a and 30 vertical sides a' a'. In the upper edges of the sides, near the ends, are notches to receive the base-flanges b of the rails B. In the trough of the tie are blocks C, (of wood or other suitable material,) which act as cushions or supports for the rails, layers of packing being inserted between the blocks and rails, if desired.

35 D D are clips resting upon the edges of the flanges of the rails and at their lower ends 40 d d' engaging the bolts E, which pass transversely through the tie and have suitable heads and nuts outside the sides of the tie. The lower ends d of the clips, as shown on the left of the drawings, Fig. 2, are turned so as to pass between the block C and bolt E and thence outward away from the block, while the lower

ends d' on the right of the drawings pass down outside the bolts E and thence inward toward the block C. A bolt F passes horizontally through the block C and clips D, having its head bearing upon one clip and its nut f against the other clip. By the projection of the lower ends of the clips the flanges of the rails are securely held down and the rails kept from raising from the cushions or out of the notches of the ties, while pressure applied to the clips horizontally by the bolts F tends to cause the upper inclined ends of the clips to ride up on the base-flanges of the rail, thus continually preserving a secure and tight fastening of all the parts. The transverse bolt E, in addition to securing the clips against rising, also serves to strengthen the sides of the ties.

Having thus fully described my invention, 65 what I claim, and desire to secure by Letters Patent of the United States, is—

1. The combination of the tie, the cushion-block therein, the rail resting on the cushion-block, the clips engaging the base-flanges of the rails at their upper ends and formed as hooks at their lower ends, and transverse bolts passing through the sides of the tie and engaging the hooked lower ends of the clips, as set forth. 75

2. In combination, the tie, the cushion-block, a rail resting thereon, a clip bent to pass upon and engage the top of the base-flanges of the rail and having its lower end passed downward against the cushion-block and turned outward, a transverse horizontal bolt passing through the sides of the tie and engaging the lower ends of the clips, and a longitudinal bolt passing through the clips and the cushion-block, as set forth. 85

In testimony whereof I affix my signature in presence of two witnesses.

ROBERT MORRELL.
